UNITED STATES PATENT OFFICE.

HENRY ZWEIG AND ISIDORE SCHNEIDERMAN, OF BROOKLYN, NEW YORK, ASSIGNEES
OF ONE-HALF TO FRANK ROSS AND ONE-HALF TO BENNI BRETN, BOTH OF BROOK-
LYN, NEW YORK.

WATCH RING.

Application filed December 2, 1922. Serial No. 604,461.

To all whom it may concern:

Be it known that we, HENRY ZWEIG and ISIDORE SCHNEIDERMAN, citizens of Russia, and residents of Brooklyn, in the county of 5 Kings and State of New York, have invented certain new and useful Improvements in Watch Rings, of which the following is a specification.

This invention relates to jewelry, more 10 particularly to watches, and the main object is to provide a casing for a ring which permits the housing of a watch movement therein. Watch rings have been made heretofore, but this particular disclosure 15 illustrates and describes a design which permits ready assembling of the parts during the process of manufacture.

Another object is to provide a special 20 type of casing mounted on a ring which has a removable upper part normally retained in closed position by a lever, the latter also forming part of the winding stem of the movement.

These and other objects will become 25 apparent in the description below, in which characters of reference refer to like-named parts in the drawing.

Referring briefly to the drawing, Figure 30 1 is an end elevational view of the watch ring, the upper casing being shown in broken lines partly open.

Figure 2 is a side elevational view of the same.

Figure 3 is a top plan view of the watch 35 ring.

Figure 4 is a perspective view of one of the upper casing retaining means.

Figure 5 is a front elevational view of the casing hinge pin member.

Figure 6 is a cross-sectional view taken 40 on the line 6-6 of Figure 2.

Describing the drawing in detail, the 45 numeral 10 indicates the band of a ring. The upper part of the band has an elliptical body casing 11 formed thereon, the major axis of the casing running parallel with the centre of the band. This casing is hollow in the interior and receives a watch movement therein. The body casing may be constructed in any of a variety of ways as no difference in this respect is desired.

The cover casing 12 is of similar shape and contour as the body, and is provided with a crystal 13 which is bezeled into place

on the upper wall 14, the wall being convergently inclined to enhance the appearance of the article. The lower edge of the cover rests upon the upper edge of the body and is normally retained in place by a pair of retainer hinge plates 15 and 16 which are positioned on and rise from the band 10 where the latter is joined to the body. Said hinge plates are constructed similar to each other but the lower end of the member 15 is permanently fixed to the band of 60 the ring. The remainder of said member extends upwardly in a slight curve to a position slightly above the upper edge of the body casing where it is formed into a pair of spaced apart hinge sleeves 17, said 65 hinge sleeves being formed so the joint occurs at the rear and they are entirely concealed when looking at the face 18 of the hinge plate. An elongated ball 19 is rigidly fixed on the wall at the lower edge of 70 the cover casing, and is of such width as to snugly fit into the space between the hinge sleeves 17. Pins 20 extend from the 75 ends of the ball in opposite directions and receive the hinge sleeves 17 thereon. The hinge ball 19 on the opposite side of the cover is provided with an internally threaded hole 21 which engages the threaded winding stem of the watch movement, and is entirely detached or free of the cover casing. 80 The hinge plate 16 which rotates about the pins of the ball 19 is constructed similar to the opposite one, but the lower end thereof has a pair of oppositely disposed slightly 85 resilient ears 22 which are spaced so as to grip the sides 23 of the ring band 10 therebetween.

Manipulation of the various members of this article is simple with this type of construction. When a watch movement is to be inserted into the body casing 11, the cover casing can be readily opened, as shown by the broken lines in Figure 1, by being rotated upon the hinge sleeves 17 of the plate 15. Said plate 15 is identical in shape, design, and construction to the opposite plate 16, but the ears 22 at the lower end are permanently attached to the band 10. The other hinge plate 16 is attached to the winding stem of the watch movement thru the medium of the ball 19 which is directly attached to the winding stem. Obviously, when the hinge plate 16

is rotated on the axis of the binding stem the main spring of the watch movement is tensioned.

One of the greatest difficulties with the construction of watch rings where the hinge plate engages a permanent position catch, is that when the band is being sized, the position of the catch is altered with respect to the catch means on the hinge plate with the consequent improper fit. This is eliminated with the side ears 22 which grip the band 10 at any position on the periphery of the band and without regard to the sizing desired.

15 We claim:—

1. An article of the class described comprising an annular band having a body casing thereon, the latter being receptive of a watch movement, a casing covering said movement, a ball member at one side of the cover, a similar ball secured to the winding stem of the movement, both members having pins projecting from the sides thereof, a hinge plate fixed to the side of the band, 25 being adapted to engage the ball member

attached to the cover, a similar hinge plate engaging the winding stem, side ears on the latter being adapted to normally grip the sides of the band at any point on the periphery thereof, and prevent rotation of the winding stem. 30

2. An article of the class described comprising an annular band having a body casing thereon, the latter being receptive of a watch movement, a casing covering said movement, a winding stem connected with said watch movement, a handle hinged to said winding stem, and side ears on said handle adapted to engage said band therebetween to prevent rotation of said handle. 35 40

3. A ring having a watch case, a winding stem therefor, a handle hinged to said stem, and side ears on the free end of said handle adapted to engage said ring therebetween to prevent rotation of said handle. 45

Signed at New York, in the county of New York, and State of New York, this 24th day of November, A. D. 1922.

HENRY ZWEIG.

ISIDORE SCHNEIDERMAN.
